UNITED STATES PATENT OFFICE.

THEODORE S. BALSLEY, OF DETROIT, MICHIGAN.

DESIGN FOR A FLOWER-POT.

SPECIFICATION forming part of Design No. 20,523, dated February 17, 1891.

Application filed January 6, 1891. Serial No. 376,933. Term of patent 7 years.

To all whom it may concern:

Be it known that I, THEODORE S. BALSLEY, a citizen of the United States, residing at Detroit, in the county of Wayne and State of Michigan, have invented a certain new and useful Design in Flower-Pots, of which the following is a specification, reference being had therein to the accompanying drawings.

Figure 1 is a perspective view of a flower-pot, showing my design. Fig. 2 is a side elevation of the same.

The leading feature of my design consists in an ornamental bottom; and the design consists of the representation of a horseshoe formed around the bottom of the pot, the calks of the shoe being arranged at the edges and forming the legs whereby the bottom of the pot will be raised from the plane upon which it is set.

A is the body of the flower-pot.

B is the bottom, C showing the raised outline of the horseshoe.

D are the calks.

The horseshoe-nails are represented at E to make a more perfect simulation of the article.

What I claim as my invention is—

The design for a flower-pot, substantially as herein shown and described.

In testimony whereof I affix my signature in presence of two witnesses.

THEODORE S. BALSLEY.

Witnesses:

M. B. O'DOGHERTY,

S. M. HULBERT.
